Fig. 4

The design is characterized by three pouring lips and a handle-receiving element in the arrangement shown and having the configurations shown.

I claim:

The ornamental design for a saucepan or the like, as shown and described.
